UNITED STATES PATENT OFFICE.

LUKE W. TAYLOR, OF UPPER FALLS POST-OFFICE, VERMONT.

IMPROVEMENT IN MOP-HEADS.

Specification forming part of Letters Patent No. 117,943, dated August 8, 1871.

To all whom it may concern:

Be it known that I, LUKE W. TAYLOR, of Weathersfield, Upper Falls Post-Office, in the county of Windsor and State of Vermont, have invented a new and Improved Mop-Head; and that the following is a full and exact description of the same, reference being had to the accompanying drawing and to the letters of reference marked thereon making a part of this specification.

The object of this invention is to construct a mop-head that shall be simple, cheap, and useful. The invention consists in coiling the ends of the movable jaw or binder of a mop-head into a spiral, so that it may be operated with a positive up-and-down motion, by projections on a revolving collar working between said coil or spiral, as in a screw.

In the accompanying drawing, Figure 1 represents a side view of my invention, and Fig. 2 an edge view of the same in section.

Similar letters of reference indicate like parts in the several figures.

A represents the cross-head or fixed jaw of a mop-head; B, the socket, cast onto the cross-head; C, the handle. These several parts being common in mop-heads, no further description is here required and no claim is made to them. The binder or movable jaw D, it will be observed, passes around the cross-head in the direction of its length, working into guides formed in said cross-head; thence it is bent in a direction parallel with the length of the cross-head to the socket B; and the ends of said binder are next coiled in the form of a spiral spring, F, fitting around said socket and the handle C. The handle is reduced somewhat in size at one end, forming a shoulder, e. Onto this reduced end is fitted a collar, b, so that it may freely revolve thereon between the shoulder e and the lower edge of the socket B of the cross-head, when said handle is

fitted into said socket, thus confining said collar in place. The collar b is of peculiar construction, being cast or otherwise formed with two thumb-ears, d d, by which it may be revolved, and also with two lesser projections or ears, e e, placed at or nearly at right angles to the first-mentioned ears d d, so that when the collar b is revolved the projections e e will pass between each coil of the spirally-bent extremities of the binder or movable jaw D, and in this way force said binder up and down as the collar b is turned to the right or left, bringing it more or less in contact with the cross-head or fixed jaw A.

From the foregoing it must be seen that I construct a mop-head cheaply and strongly, and obviate the necessity of attaching several parts heretofore found necessary in mop-heads, besides reducing the cost by doing away with much riveting, and other fitting and manipulation; and since mop-heads are a common, though useful article of manufacture, the cheaper they can be made, (providing said cheapness is combined with excellence,) the better are the wants of the public subserved; hence my improvements are useful, novel, and cheap.

Having thus described my invention, what I claim as new, and desire to secure by Letters Patent, is—

1. The binder D, formed at one end into the spiral f embracing the handle C, in combination with the collar b having lugs e e and ears d d, substantially as set forth, for the purposes specified.
2. The combination of the collar b, formed with lugs e e and ears d d, with the binder D having a spiral, f, when arranged to operate in connection with the cross-head and handle, substantially as and for the purpose set forth.

LUKE W. TAYLOR.
